UNITED STATES PATENT OFFICE.

WILLIAM NEWTON BEST, OF LOS ANGELES, CALIFORNIA, ASSIGNOR TO JOHN H. BEST AND EZRA BEST, OF QUINCY, ILLINOIS.

METALLURGICAL FURNACE.

No. 894,107.

Specification of Letters Patent.

Patented July 21, 1908.

Application filed December 31, 1903. Serial No. 187,311.

To all whom it may concern:

Be it known that I, WILLIAM NEWTON BEST, a citizen of the United States, residing at Los Angeles, in the county of Los Angeles and State of California, have invented a new and useful Metallurgical Furnace, of which the following is a specification.

This invention relates to a metallurgical furnace heated by oil as fuel.

10 An object of the invention is to provide a practical metallurgical furnace using oil as fuel.

A further object is to provide means for regulating the character of the product of the 15 furnace.

In previous methods of melting cast iron in cupolas where coke is used, although the charge of coke and iron is weighed in order to obtain a cast iron of a certain proportion 20 of carbon, yet it is known in practice that the iron of the last of the heat is always different from the iron of the first of the heat for the reason that the carbon in the coke is absorbed by the iron, and, as a result, the iron of the 25 last of the heat contains excessive carbon, so that often the iron of the last pouring from the heat is absolutely worthless, being so hard that the metal cannot be turned and laid. By the use of oil fuel this difficulty of uneven 30 quality of metal may be overcome, and an object of this invention is to provide a furnace in which the carbon in the molten metal may be reduced until the metal becomes quite malleable, and thereby make a superior quality of cast iron and to reduce the 35 carbon where necessary until a cast metal is produced that can be bent without breaking.

One object of my invention is to provide a 40 metallurgical furnace, which, while affording the greatest concentration and application of the heat units applied thereto, will effectively oxidize and decarbonize the metals reduced therein.

Another object of my invention is to provide 45 a furnace of economical construction, together with great strength to resist the variations of temperature to which it is subjected.

My invention, broadly stated, consists in a 50 metallurgical furnace of the combination of a fire and reducing-chamber and a crucible and oxidizing-chamber connected therewith and

arranged to receive the molten metal from the fire and reducing-chamber, and to hold the same as a reservoir or for treatment to 55 oxidize or decarbonize the same.

My invention also includes in a metallurgical furnace comprising a fire-chamber and reducing-chamber, means for introducing fuel into such fire-chamber, regulable means for 60 introducing air thereto, and means for controlling the exit of the heat and fumes from the reducing-chamber.

The accompanying drawings illustrate my 65 invention.

Figure I is a longitudinal, sectional view of the fire and reducing-chamber of the furnace. Fig. II is a plan view of the furnace, showing one metal crucible-chamber at its side. Fig. III is a plan view of the furnace 70 with two crucibles attached thereto, one on each side of the reducing-chamber. Fig. IV is a longitudinal section of the crucible-chamber and across the reducing-chamber, taken on line IV—IV, Fig. I. Fig. V is a 75 section of the reducing-chamber taken on line V—V, Fig. I. Fig. VI is a view of the end of the crucible-chamber showing an opening for the introduction of hydrocarbon fuel.

1 is the reducing chamber provided with 80 an inclined floor *a* sloping downward toward a fire chamber 2 having a substantially horizontal floor *b* which extends somewhat above the level of the floor *c* connecting between the floor *a* and *b* slanting upward toward the 85 floor *a* of the fire chamber at a reduced degree of angularity.

3 designates one or more lateral crucible chambers which communicate with the intermediate portion of vestibule *d* within 90 the apparatus between the fire chamber 2 and the reducing chamber 1. 4 designates a passage communicating between the fire spaces of the fire chamber and the reducing chamber and the fire space of the crucible 95 chamber through the intermediate portion of vestibule *d*. Said chambers are all inclosed; that is to say, are walled in, floored and roofed, and means are supplied as hereinafter described, for closing all the outlets 100 therefrom at the will of the operator.

5 is a hydrocarbon burner arranged to project combustibles into the fire and reducing-chambers 1 and 2.

6 is a hydrocarbon burner arranged to project flame into the crucible-chamber 3.

7 is an air-pipe arranged to supply air above the burner 5 in the fire-chamber.

5 8 is an air-pipe arranged to introduce air into the crucible-chamber 3 above the molten metal.

9, 9 are air-pipes arranged to introduce air into the crucible-chamber at a point below 10 the burner 6.

The fire passage 4 between the crucible chamber 3 and the vestibule *d*, extends upward nearly to the tops of said crucible chamber and vestibule, and the floor of the 15 crucible chamber has a sloping portion forming a sharp incline leading downward from the floor of the passage 4 toward the oil burner 6, to give upward direction to the blast from such burner; said fire passage 4 being contracted relative to the crucible chamber 3 and vestibule *d*.

The floor *a* of the reducing chamber has a greater inclination than the floor *c* of the vestibule, in order that the force of gravity 25 may assist in starting the movement of the molten material in the reducing chamber, and that the tendency of the molten material to flow rapidly will be reduced as the material becomes more liquid, and at the vestibule a 30 change of direction will take place in said molten material at the point where the fires from the crucible chamber and from the fire chamber will impinge upon each other, causing an intense heat upon the molten 35 material in the vestibule, whereby said material becomes highly heated and highly fluid, and therefore ready for further treatment by introduction of the air through the air pipes 9 which are arranged to open 40 through the slanting portion *e* of the crucible floor to apply air to the molten material in its highly fluid state, which is increased by the concentration of the flame from the oil burner 6 directed thereonto.

45 10, 10, 10 are doors arranged to admit the unreduced charges of metal into the reducing-chamber 1.

11 is a slag outlet from the crucible-chamber 3.

50 12 is a spout to draw the metal from the crucible-chamber 3.

13 is a door or outlet in the bottom of the crucible-chamber 3.

55 14, 14 are supports for the body of the reducing-chamber.

15, 15 are channel irons carried on cross-beams 16.

17 is an iron or steel sheeting floor which supports and carries the brick-work 18 of the 60 body of the furnace.

19 indicates the arched brick of the roof of the furnace-chamber.

20, 20 are ribs held together by means of bolts or stays 21, 21 at top and bottom of 65 the furnace-body.

22 is a covered man-hole to the crucible-chamber 3. 23 is the smoke-stack. 24 is the damper therefor.

25 indicates an opening in the end of the reducing-chamber for the introduction of hydrocarbon fuel and air feeding means. 70

26 is a channel or depression leading from the fire-chamber into the crucible-chamber.

The charge to be reduced is placed in the reducing-chamber 1 and the fuel is supplied 75 through the end of the chamber as indicated by the hydrocarbon burner 5 at the opening 6, and a suitable quantity of air is supplied above the burner. When the metal is reduced to a liquid state it flows down from 80 the chamber 1 into the fire-chamber 2 and is drained therefrom into the crucible-chamber 3 through the passage 4.

When the reducing and fire chambers 1 and 2 have been heated to a high degree of 85 heat, the damper 24 is partially closed and the amount of combustibles admitted to the fire-chamber is regulated to the requirement to maintain the heat at the proper temperature, and air is admitted through the air-pipe 90 5 in sufficient quantity to produce perfect combustion; the heat is retained in the reducing-chamber and with a small amount of fuel the temperature is maintained at the proper degree. 95

I am not aware that any metallurgical furnace of this class has heretofore been produced which will allow of the closing of the draft flue and rely upon the supply of oxygen to promote combustion, and I believe my invention to be broadly new in this respect. It is well known in the art of thermochemistry that it is necessary to furnish a supply of oxygen to continue combustion, and in furnaces of this character it is ordinarily customary to supply the oxygen by a forced draft and to allow of the free egress of heat and fumes from the top of the chamber through a smoke-stack or flue. 100

105 By my invention I am enabled to reduce valuable ores in the fire and reducing-chamber without the consequent loss by what is commonly known as flue-dust, which dust is carried away from the ores while in the course of reduction by the excessive draft required to supply oxygen to the combustibles in the reducing-chamber. 110

115 When it is desired to decarbonize or oxidize a metal or mineral, I apply heat to the crucible-chamber 3 through the medium of a hydrocarbon burner or other means and maintain the molten liquid at a high degree of temperature which, in case of there being a low percentage of carbon contained in the iron, will readily remove such excess. In 120 case a large percentage of carbon is contained in the iron or other metal, I fill the crucible-chamber with molten metal, and while such metal is flowing downward into the chamber through the depression 26 in the floor, I apply 125

ply air through the medium of the air-inlet pipes 9 which passes through the body of flowing metal.

When the metal in the crucible-chamber has reached a point above such air-inlets, the force of the air current may be continued against the body of metal, which will start it into rotation and the air will be brought into contact with the metal and hasten the oxidation and decarbonization of the same. Preferably I arrange the air-inlets 9, 9 tangentially to the vertical axis of the body of the crucible-chamber to assist in the agitation of the molten metal when applying the air.

In ordinary practice, when the furnace is used for melting pig iron for casting purposes, the fire will be introduced into the fire-chamber 2, thereby heating the reducing-chamber 1, and the auxiliary fire will be introduced into the crucible-chamber 3 until the chambers are thoroughly heated, when the fire from burner 6 may be stopped and fire from the burner 5 continued, the charge of metal being placed in the reducing-chamber 1 through the doors 10, 10.

When the metal has been melted to the liquid point it will run downward on the floor of the chamber 1 into the fire-chamber and thence be drained into the crucible-chamber 3 where it will remain until drawn therefrom through the spout 12.

By my invention I provide a furnace by the use of which iron of the same texture can be produced for each separate run. When the crucible-chamber 3 has received a suitable charge of iron and it is desired to reduce the carbon therein, the burner 6 or other medium for admitting an oxidizing blast of flame from the oil burner, mingled with air, to the chamber is put in operation and the metal is kept at a high degree of heat until the carbon is reduced in the metal to the degree desired.

My improved metallurgical furnace is especially adapted for the reduction of those ores which carry a percentage of sulfur such as copper ores. In reducing copper ores, the ore will be placed in the chamber 1 and the metal carrying a percentage of sulfur will run down the floor of the chamber into the fire-chamber 2 and thence into the crucible-chamber 3 where the air-pipes 9, 9 will supply air under pressure to the molten metal and will agitate and oxidize the same, thereby relieving it of the sulfur, the heat-supplying means at the end of the chamber assisting in the action.

When my furnace is used in melting iron or steel for casting purposes, and it is desired to prepare a large quantity of metal, I provide a crucible-chamber upon either side of the reducing-chamber, as shown in Fig. III; this enables me to melt a large quantity of iron and contain it in the crucible-chambers until ready for use.

When the crucible-chamber is heated by the burner 6 it assists very materially in heating the fire-chamber 2 and the reducing-chamber 1, as the heat from this chamber is communicated through the passage 4 into the fire-chamber 2 and reducing-chamber 1, but it will not at all times be necessary to maintain the supplemental burner in the crucible-chamber.

When it is desired to clean the floor of the crucible-chamber 3, the bottom 13 is removed and the man-hole 22 is opened, which allows a draft of air through the crucible-chamber which will quickly cool it and allow of the ingress of a man to perform such work.

In the construction of the furnace I prefer to support the same upon uprights 14, 14 which are connected together at their tops by cross-beams 16 upon which are laid channel irons 15, 15 running lengthwise of the reducing-chamber. Upon these channel irons I place a sheet metal floor 17 upon which is constructed the furnace-walls of fire-brick or other suitable material, and the walls are bound together by means of bolts 21, 21 and the side bars 20, which prevent the walls of the furnace from cracking by the expansion and contraction occasioned by the variation in heat.

The arches of the crucible-chamber and the reducing-chamber are made of the ordinary arch bricks and the tie-rods 21, 21 are firmly drawn up to clamp and hold the bricks in position.

The doors 10, 10 are arranged to be retained in position to close the openings into the furnace-body by their own gravity; that is to say, the mouth of the openings are arranged aslant and the doors are thus allowed to lie aslant against them. This effectually closes the openings and prevents any puffing out of the heat or flame.

When two crucible chambers are employed a dam or dividing partition may be placed in the fire-chamber to divert or divide the molten metal when flowing into one or the other of such chambers by opening the lower door on the top of the furnace.

Now having described my invention what I claim as new is:—

1. A metallurgical furnace comprising a reducing chamber having an inclined floor, a fire chamber toward which said floor slants downward, a vestibule between said fire chamber and reducing chamber, the floor of the vestibule being lower than that of the fire chamber, a laterally-disposed crucible chamber, a fire passage opening communicating between the crucible chamber and the vestibule, said passage-way being provided with a floor sloping downwardly from the vestibule into the crucible chamber, an oil-burner inlet opening into the fire chamber at the end opposite the reducing chamber, an oil burner arranged to direct fire through

said opening into the fire chamber, an oil-burner inlet opening into the crucible chamber in the end opposite the passage into the vestibule, and an oil-burner arranged to direct fire downwardly into the crucible chamber.

2. A metallurgical furnace comprising a reducing chamber, vestibule and fire chamber arranged in line with each other, the 10 reducing chamber being provided with a floor sloping downwardly toward the vestibule, a passage opening laterally from the vestibule, a crucible chamber communicating with said passage, and oil burners for 15 said fire chamber and for said crucible chamber, one being arranged to direct fire along the fire chamber and across the passage, and the other being arranged to direct fire into the crucible chamber and toward 20 the vestibule.

3. A metallurgical furnace comprising a reducing chamber, having an inclined floor, a fire chamber toward which said floor slants downward, a vestibule between said 25 fire chamber and reducing chamber, the floor of the vestibule being lower than that of the fire chamber, a laterally-disposed crucible chamber, a fire passage opening communicating between the crucible chamber 30 and the vestibule, said passage-way being provided with a floor sloping downwardly from the vestibule into the crucible chamber, an oil-burner inlet opening into the fire chamber at the end opposite the 35 reducing chamber, an oil burner arranged to direct fire through said opening into the fire chamber, an oil-burner inlet opening into the crucible chamber in the end opposite the passage into the vestibule, an oil 40 burner arranged to direct fire downwardly into the crucible chamber, and means for

directing air into the crucible chamber through the slanting floor thereof toward the oil burner for said crucible chamber.

4. A metallurgical furnace comprising a 45 reducing chamber, a vestibule and a fire chamber arranged in line with each other, an oil burner to direct fire into the fire chamber toward said vestibule and reducing chamber, crucible chambers on opposite 50 sides of said vestibule and communicating with said vestibule, and oil burners in the ends of said crucible chambers respectively opposite the vestibule and arranged to direct fire toward the vestibule. 55

5. In a metallurgical furnace, in combination with the fire and reducing-chambers thereof, an inclosed crucible-chamber communicating with the fire-chamber having fire-admitting means, and means for admitting air under the inflowing molten metal. 60

6. In a metallurgical furnace, in combination with the fire and reducing-chambers thereof, an inclosed crucible-chamber communicating with the fire-chamber having 65 air openings for admitting air under pressure to such chamber and directing the same horizontally into the flowing molten metal, such openings being horizontal and arranged obliquely to the walls of the chamber and 70 hydrocarbon burners for heating said chambers.

In testimony whereof I have hereunto signed my name in the presence of two subscribers, at Los Angeles, in the 75 county of Los Angeles, and State of California, this 23rd day of December, 1903.

WILLIAM NEWTON BEST.
